TELEVISION BROADCAST SYSTEM

Arthur V. Loughren, Tuckahoe, N. Y., assignor to
Hazeltine Corporation, a corporation of Delaware

Application June 9, 1938, Serial No. 212,691

30 Claims. (Cl. 178—6.8)

This invention relates to television systems and is particularly concerned with the provision of an improved type of television signal together with transmitting apparatus and receiving apparatus for generating and utilizing such signal, respectively.

In accordance with present television practice, there is developed and transmitted a signal which comprises a carrier wave modulated during successive intervals or trace periods by video-signal components representative of the light and shade values of an image being transmitted. During retrace intervals between the trace periods, the carrier wave is modulated by synchronizing impulses or components which correspond to initiations of successive lines and fields in the scanning of the image. At the receiver, a beam is so deflected as to scan and illuminate a target in a series of fields of parallel lines, the video-signal components being utilized to control the intensity of the beam. The line-scanning and field-scanning synchronizing components are separated from the video-frequency components and from each other and are utilized to synchronize the operation of the receiver line-scanning and field-scanning apparatus with similar apparatus utilized at the transmitter in developing the signal. The transmitted program or image is thereby reconstructed on the target of the receiver.

Various types of television signals, as well as various types of scanning and synchronizing methods and apparatus, have been proposed. For example, in certain systems negative modulation is employed, that is, a decrease in carrier amplitude during the trace periods, when the carrier is amplitude-modulated by the video-signal components, corresponds to an increase in illumination. In other systems, positive modulation is utilized in which an increase in carrier amplitude corresponds to an increase in illumination. The synchronizing-modulation components of the signals used in these systems ordinarily have amplitude values outside the range of video-modulation components. Where negative modulation is employed, they are represented by increase in carrier amplitude while, where positive modulation is employed, they are represented by decreases in carrier amplitude, in either case usually having amplitude values corresponding to "blacker-than-black."

In present practice with negative modulation, synchronizing signals represent an increase in transmitted power of approximately 55% over the maximum power required for the video-mod-

ulated or trace portions of the signal. This is undesirable not only because of the uneconomical requirement of increased power, but also due to the fact that interference presented by the signal of one program with another is a function of the peak value of the power radiation of the signal of the interfering program.

In television receiving systems noise components disturb both the video-signal and the synchronizing-signal compounds. In general, noise impulses are represented by increases in carrier amplitude so that, in positive modulation systems, the noise components appear in the image as white spots while, in negative modulation systems, they appear as black spots. The white spots are usually the more annoying to an observer so that, as far as the video signal is concerned, a negative modulation signal is less affected by noise. On the other hand, with negative modulation the synchronizing components are represented by increases in carrier amplitude and are thus most subject to noise effects, while with positive modulation synchronizing components are represented by a reduction of carrier amplitude, usually to zero, so that they are substantially less affected by noise. Therefore, as far as the synchronizing components are concerned, a positive modulation signal is less affected by noise.

It is an object of the present invention, therefore, to provide an improved television system utilizing a carrier wave having the desirable characteristics incident to negative modulation with respect to the video-signal components and including synchronizing components which are not appreciably affected by the effects of noise disturbances.

It is a further object of the invention to provide a system of the character described where 40 in the carrier wave is negatively modulated during trace periods by video-signal components and is modulated by suitable synchronizing components during retrace scanning intervals without any appreciable increase in the transmitted power over that required for the video-modulation components of the wave.

In accordance with a feature of the present invention, there is provided a television transmitting system comprising means for developing a carrier wave, means for developing video-frequency components during trace periods, and means for developing synchronizing-signal components during retrace periods. The system also includes means for amplitude-modulating the carrier wave in accordance with signal compo-

nents of one of these types and for maintaining its frequency constant during all of the periods corresponding to such type and means for frequency-modulating the carrier wave in accordance with signal components of the other type and for maintaining its amplitude constant during all of the periods corresponding to such other type. The transmitter also comprises means for transmitting the modulated-carrier wave. The carrier wave may, for example, normally have a predetermined frequency and be shifted with respect to this frequency during the retrace scanning periods. This frequency modulation, or shifting of the carrier frequency, corresponding to synchronizing impulses may comprise a single shift per impulse, it may be for different durations for line-synchronizing and field-synchronizing impulses, it may comprise a plurality of successive cycles of predetermined different periods, or it may comprise any suitable combination of these characteristics.

Also in accordance with a feature of the invention, a station is provided for receiving and reproducing a program transmitted by a carrier wave of the type developed by the transmitter described, this station including means for selectively receiving the carrier wave, means for detecting signal modulation of one type for deriving the video-signal components, and means for detecting the signal modulation of the other type for deriving synchronizing-signal components. Means are provided for utilizing the derived components to reproduce the transmitted program.

Also in accordance with a further feature of the invention, a television broadcast system comprises a transmitter of any of the types mentioned above and a suitable receiving station therefor.

In accordance with another feature of the invention, the transmitting system may be arranged to transmit only the carrier and that sideband of its modulation frequencies on the side to which the carrier is shifted during the retrace periods. The receiver and, if desired, also the transmitter, then include a band-pass selector for translating the carrier and its proper sideband, which selector has a response characteristic with a sloping side and a mean frequency so related to the predetermined carrier frequency that the latter is located on the sloping side. By virtue of this arrangement, there is obtained an effective increase in the amplitude of the carrier wave during synchronizing-signal modulation periods with respect to the video-modulation periods, without the requirement of increased power transmission at the transmitter.

For a better understanding of the invention, together with other and further objects thereof, reference is had to the following description taken in connection with the accompanying drawings, and its scope will be pointed out in the appended claims.

In the accompanying drawings, Figs. 1 and 2 are circuit diagrams, partially schematic, of complete television transmitting and receiving systems, respectively, embodying the present invention; Figs. 2a and 2b are diagrams illustrating modifications of parts of the receiver of Fig. 2; Figs. 3-7, inclusive, are graphs illustrating the wave forms of signals developed by the apparatus of the present invention; and Figs. 8-10, inclusive, are graphs illustrating certain operating characteristics of the systems shown in Figs. 1

and 2 to aid in the understanding of the invention.

Referring now more particularly to Fig. 1 of the drawings, there is illustrated a television transmitting system or station for developing and transmitting a modulated-carrier wave. This station comprises means for developing video-signal components during trace periods, such as a signal-generating device of conventional design indicated generally at 10 which may include a cathode-ray signal-generating tube 11 having the usual electron gun and photosensitive target and line-scanning and field-scanning elements 11a and 11b, respectively. There are also provided a line-scanning wave generator 12 and a field-scanning wave generator 13 with their output circuits connected directly to the line-scanning elements 11a and field-scanning elements 11b, respectively. In order to provide pedestal impulses for blocking out, or for suppressing undesirable impulses in, and ensuring the proper wave form of, the modulation signal developed by the generator 10, there is provided a pedestal-impulse generator 14 having its output circuit coupled to the control grid of the signal-generating tube 11. Synchronizing-signal-generating apparatus is provided in accordance with the present invention and will be hereinafter described in detail.

In order to synchronize the operations of the generators 12, 13, and 14 and the synchronizing-signal-generating apparatus, there is provided a timing-impulse generator 15 having a plurality of output circuits coupled to the generators 12, 13, and 14 and to the units of the synchronizing-signal-generating apparatus, as presently to be explained.

A modulation-frequency amplifier 16 is coupled to output circuits of the cathode-ray signal-generating tube 11 and the pedestal generator 14. The transmitter also includes means comprising a local or master oscillator 18 for generating a signal-carrier wave and means including a video-frequency amplitude modulator 17 for amplitude-modulating the carrier wave generated in local oscillator 18 with the video-frequency components generated in unit 10 and amplified in unit 16, while maintaining the frequency constant during all of the trace periods. There is also included a single sideband filter 19, a frequency changer 20, a heterodyne frequency filter 21, a power amplifier 22, and an antenna system 23, 24, as shown, the frequency changer 20 comprising means for effecting a change of frequency of, and frequency-modulating, the carrier wave generated in master oscillator 18 in accordance with synchronizing-signal components, while maintaining its amplitude constant during all of the retrace periods.

Neglecting for the moment the stages 19, 20, and 21 and the synchronizing-signal-generating apparatus provided in accordance with the present invention, the system just described includes the apparatus of a television transmitting system of conventional design, those parts of the system illustrated schematically being of any well-known suitable construction, so that a detailed description of the system and its operation is unnecessary herein. Briefly, however, the image of the scene to be transmitted is focused upon the target of the tube 11, in which a cathode ray or beam is developed, accelerated, and also focused upon the target. Scanning or deflection currents developed by the generators 12 and 13 are applied to the scanning elements or windings

11a and 11b and serve to deflect the ray to scan successive series of fields of parallel lines on the target. Pedestal impulses developed by the generator 14 are applied to the control electrode of the tube 11 to suppress or block out the beam during certain portions, particularly retrace portions, of the scanning cycles and are applied to the modulation-frequency amplifier 16 to suppress undesirable impulses developed in the system and to aid in obtaining the required wave form of the video-modulation signal.

The photosensitive elements of the target being electrically affected to an extent depending upon the varying values of light and shade at corresponding incremental areas of the image focused thereon, as the cathode ray scans the target, a voltage of correspondingly varying amplitude is developed in the output circuit of the signal-generating tube and applied to the amplifier 16. Suitable timing or synchronizing impulses are applied from the generator 15 to the generators 12, 13, and 14 to maintain these generators in synchronism with either the master frequency, in the case of direct camera shots, or the motion picture camera, in the case where such pictures are being transmitted. The video-signal components applied to the amplifier 16 are amplified therein and thereupon supplied to the modulator 17 wherein they are impressed upon the carrier wave generated by the oscillator 18. The signal is translated from the modulator 17 to the power amplifier 22, by way of the stages 19-21, inclusive, and in accordance with the present invention, the transmitter includes means for amplitude-modulating the generated carrier wave in accordance with video-signal components during trace periods, while maintaining its frequency constant during all of the trace periods, and means for frequency-modulating the carrier wave in accordance with synchronizing-signal components during retrace periods, while maintaining its amplitude constant during all of the retrace periods, as will be presently explained. The resultant modulated-carrier wave is amplified in the power amplifier 22 and is thereupon impressed upon the antenna system 23, 24 for radiation.

Coming now to that part of the system embodying the present invention, it will first be noted that the single sideband filter 19 may be of any suitable well-known design, preferably having a characteristic such as is shown by the curve of Fig. 8, wherein relative gain is plotted against frequency, as indicated, that is, a characteristic such that the band-pass selector or filter 19 translates the carrier signal and that one of its modulation sidebands on the side of the frequency to which the frequency of the carrier wave is shifted to translate synchronizing signals, as hereinafter more fully described. Specifically the selector is designed to have a response characteristic with a sloping side and a mean frequency so related to the carrier frequency developed by the modulator 17 that this frequency is located on the sloping side thereof, as indicated at X in Fig. 8, so that, although the sideband frequencies corresponding to the lower modulation adjacent the carrier frequencies are passed with relatively less gain, a portion of both sidebands representing these frequencies is passed by the selector so that the over-all gain is substantially the same for these lower modulation frequencies as for the higher modulation frequencies. The heterodyne frequency filter 21 is of any suitable conventional type designed to pass either the difference or sum

frequencies developed by the frequency changer 20, preferably the latter.

The means for developing synchronizing-signal components during retrace periods includes, in 5 addition to the generators 12 and 13 already referred to, a line-frequency harmonic generator 25 and a field-frequency harmonic generator 26, each of which has an input circuit connected to the timing-impulse generator 15 for synchronization. The generators 25 and 26 are of any conventional design suitable to develop periodic waves preferably of sinusoidal wave form and at harmonic frequencies of the line-synchronizing and field-synchronizing impulses, respectively. 10 In a preferred arrangement, for example, the line-scanning and field-scanning frequencies may be 13,230 and 60 cycles per second, respectively, and the frequencies developed by the generators 25 and 26 may be 1.00548 megacycles and 0.240 megacycle, respectively, that is, the 76th and 4000th harmonics of the line-scanning and field-scanning frequencies, respectively, as will be hereinafter further explained.

While the generators 12 and 13 develop currents of the saw-tooth wave forms indicated at 15 the left of these generators and at their respective frequencies, they also, in accordance with well-known practice, generate rectangular-impulse waves of the form shown at the right of these generators and of the same frequencies. 20 These impulse waves are timed to fall within, and have durations somewhat less than, the line-retrace and field-retrace periods, respectively, although they are preferably caused to have durations as nearly equal to those of the line-retrace 25 and field-retrace periods as possible. Output circuits of the generators 12 and 25 are connected to a mixing amplifier 27, while output circuits of the generators 13 and 26 are connected to a 30 mixing amplifier 28, the output circuits of the generators 12 and 13 supplying the impulses of rectangular wave form. The amplifiers 27 and 28 may be of conventional design and are normally biased beyond cutoff, so that the rectangular impulses of the waves supplied from generators 12 and 13 carry these amplifiers above cutoff, rendering them operative for the durations of their respective impulses. Therefore, there appear in the output circuits of the amplifiers 27 and 28 trains of sinusoidal voltage waves of line-harmonic frequency and field-harmonic frequency, respectively, the successive trains having durations equal to portions of the line-retrace and field-retrace periods, respectively, specifically, to 35 the predetermined portions thereof corresponding to the durations of the pulses developed by the generators 12 and 13, respectively.

For the purpose of frequency-modulating the carrier wave impressed upon the frequency changer 20 from the filter 19 during the retrace 40 periods in accordance with the synchronizing-signal components, there is provided the frequency-modulating or frequency-shifting apparatus indicated generally at 29. This apparatus includes an oscillator indicated generally at 30 and a frequency-adjusting network indicated generally at 31. Preferably the oscillator is of the push-pull type, comprising vacuum tubes 32 and 33, having their input circuits connected in push-pull relation by way of an inductance 34, a leak resistor 35 and grid condenser 35a being connected in parallel between a mid-tap on the inductance 34 and the cathodes of the tubes. The anode circuits of the tubes 32 and 33 are also 45 connected in push-pull relation by way of an in-

ductance 36, coupled to the inductance 34 as indicated by bracket M, a mid-tap on the inductance 36 being connected to the cathodes of the tubes by way of anode voltage supply battery 37. The inductance 36 is normally sharply tuned to a frequency spaced from the carrier frequency developed by the modulator 17, by means of a condenser 38 or other suitable circuit arrangement. An inductance 39 is coupled to the inductance 36 and connected to the frequency changer 20 for the purpose of shifting the carrier frequency delivered from the filter 19 in accordance with frequencies developed by the oscillator 30.

The frequency-adjusting network 31 preferably comprises a pair of vacuum tubes 40 and 41 having their control grids connected by way of resistors 42 and 43 to the output circuits of the amplifiers 27 and 28 and by way of by-pass condenser 44 which is effective to by-pass oscillator-frequency currents to ground. The control grids of the tubes 40 and 41 are also connected by way of coupling condensers 45, 46 to their respective anodes which, in turn, are connected to the terminals of an inductance 47. The inductance 47 is connected in push-pull relation in the anode circuits of the tubes, a mid-tap thereof being connected to the tube cathodes by way of a suitable anode voltage supply source, indicated by the battery 48. The inductance 47 is inductively coupled to the inductance 36 of the oscillator frequency-determining circuit.

In the operation of the parts of the transmitter embodying the present invention, referring first to the frequency-adjusting network 31, which it will be assumed is excited from oscillator 30, it will be seen that, since the impedances of the condensers 45 and 46 are high compared with those of resistors 42 and 43, the voltages across the resistors lead the voltage across the inductance 47 by a large angle and that the space currents of the tubes, being in phase with the tube input voltages, also lead the voltage across the inductance 47 in corresponding degree. Hence, the system simulates an impedance having capacitive reactance and resistance components, the values of which vary in accordance with the grid-bias voltage applied to the tubes. Adjustment of the grid-bias voltage on the tubes 40 and 41, therefore, varies the effective reactance of the circuit 31 and, hence, the natural frequency of the oscillation circuit 36, 38 to which it is coupled.

Normally the tubes 40 and 41 are biased beyond cutoff and remain so biased during the video-signal or trace periods, being rendered operative only during synchronizing or retrace periods when impulses from one or both of the generators 12 and 13 are applied thereto. Since the tubes 40 and 41 are cut off during the video-signal periods, the oscillation circuit 36, 38 has its own natural frequency during these periods, while its frequency is shifted in the desired manner during the occurrences of the synchronizing impulses. During the latter periods the impedance reflected into the oscillation circuit 36, 38 by the frequency-adjusting network 31 is varied in accordance with the line-harmonic and field-harmonic voltages applied to the grids of the tubes 40 and 41 from the generators 25 and 26 as controlled in amplifiers 27 and 28 by the impulses from generators 12 and 13, respectively, so that the frequency of the oscillation circuit is intermittently varied

cyclically in a manner that will presently be further explained.

The oscillator 30 being coupled as above described to the frequency changer 20, its frequency is mixed with the carrier frequency of the video-modulated signal delivered from the filter 19 and the sum and difference heterodyne frequencies are developed in the output circuit of the modulator in the well-known manner. Either the sum frequencies or the difference frequencies are selected by means of the filter 21 and delivered to the power amplifier 22 to be broadcast. Similarly, the frequency of the selected heterodyne carrier output of frequency changer 20 is cyclically varied or shifted in correspondence with the frequency variations of oscillator 30, as described above.

In Fig. 3, there is illustrated half of the envelope of the resultant modulated-carrier wave developed by the transmitting system. The video-frequency signal component is represented at the portions of the wave indicated at V and is developed during line-trace periods, the portions representing line-retrace and field-retrace periods, during which the frequency of the carrier is shifted or varied, being indicated at L and F, respectively. In Figs. 4 and 5 there are shown exploded curves illustrating the cyclic frequency variations of the carrier wave during the line-retrace and field-retrace periods L and F, respectively. In these figures, the abscissae represent time and the ordinates frequency shift or deviation of the signal carrier.

Thus, the carrier wave developed in the output circuit of the modulator 17 is amplitude-modulated by the video-signal components only during the trace scanning periods, and during these periods the frequency developed by the generator 30 and applied to the frequency changer 20 is constant so that the carrier frequency as developed in the output circuit of the frequency changer 20 is not varied. During a portion of the line-retrace periods the impulses from the generator 12 unblock the amplifier 27 and permit the line-harmonic voltages developed by the generator 25 to be passed by the amplifier 27 and impressed on the frequency-adjusting network 31, thereby to effect variations in the frequency developed by the generator 30 and, hence, in that of the carrier frequency developed in the frequency changer 20, as indicated by the curve of Fig. 4. During one or more portions of the field-retrace periods, on the other hand, the impulses from the generator 13 unblock the amplifier 28 and permit the field-harmonic voltages developed by the generator 26 to be passed by this amplifier and impressed on the network 31, thereby to effect variations in the frequency developed by the generator 30 in different predetermined manners for the line- and field-synchronizing signals, specifically in different intermittent cyclic manners and, hence, in that of the carrier-frequency output circuit of the frequency changer 20, as indicated by the curve of Fig. 5. Thus, the carrier wave developed in the output circuit of modulator 17 is frequency-modulated in frequency changer 20 by the synchronizing-signal components during all of the retrace periods. The amplitude of the carrier-frequency output circuit of frequency changer 20 is maintained constant during all of the retrace periods and the carrier signal comprising both amplitude-modulation and frequency-modulation components is directly radiated after translation in units 21 and 22.

Since the output frequencies of the generators 25 and 26 are harmonics of the line-scanning and field-scanning frequencies, the successive pulse groups are all of the same phase and waveform, and are not subjected to progressive changes in wave form from one group to the next, as would be the case if a nonharmonic cyclic variation were employed. The cycles of variation which correspond to the line-synchronizing impulse are thus of one predetermined frequency; that is, the carrier frequency is varied in one manner and for a first predetermined duration. A line-synchronizing period immediately precedes each field-synchronizing period, as shown in Figs. 3 and 5, so that line synchronization is not interrupted during field-retrace periods.

Referring now to Fig. 2, the system there illustrated comprises a television receiver of the superheterodyne type for receiving and reproducing a program transmitted by a carrier wave of the type developed by the transmitter described above. This receiver includes means for selectively receiving the carrier wave and specifically includes an antenna system 50, 51 to which there are connected in cascade, in the order named, a radio-frequency amplifier and frequency changer 52, an intermediate-frequency amplifier 53, a detector 54 comprising means for detecting the amplitude modulation to derive the video-signal components, a video-frequency amplifier 55, and a cathode-ray signal-reproducing tube 56 comprising means for utilizing the detected video-signal components to reproduce the transmitted program. Preferably, as explained below, the stages 52 and 53 are designed for single sideband reception. A line-frequency scanning generator 57 and field-frequency scanning generator 58 are also coupled to the output of the amplifier 53 by way of synchronizing-signal-deriving apparatus 59 embodying the present invention and hereinafter described in more detail. The generators 57 and 58 are coupled to the scanning elements of the cathode-ray tube 56 in a conventional manner and preferably include conventional synchronizing circuits which are adapted to be controlled by synchronizing impulses developed by the apparatus 59. The circuits 50-58, inclusive, may all be of any conventional well-known construction so that detailed illustrations and descriptions thereof are unnecessary herein.

Referring briefly to the general operation of the receiving system, television signals are selected, amplified, and converted into intermediate-frequency signals in the radio-frequency amplifier and frequency changer 52, the intermediate-frequency signals being, in turn, selectively amplified in the intermediate-frequency amplifier 53 and delivered to the detector 54. The video-modulation components of the signal are developed by the detector 54 and are supplied to the video-frequency amplifier 55, wherein they are amplified and from which they are supplied in the usual manner to a brilliancy control electrode of the cathode-ray tube 56. The intensity of the electron beam of the tube 56 is thus modified or controlled in accordance with the video-frequency voltages impressed upon the control electrode of the tube in the usual manner.

The intermediate-frequency signal is also supplied from the amplifier 53 to the apparatus 59 comprising means responsive to the frequency modulation of the received carrier for detecting

the synchronizing-signal components in accordance with the present invention, the line-synchronizing and field-synchronizing components being effectively separated from the video-frequency signals and from each other and applied to the control circuits of the generators 57 and 58 as will be hereinafter further explained. Saw-tooth current or voltage scanning waves are generated in the line-scanning and field-scanning generators 57 and 58 and applied to the scanning elements of the cathode-ray tube 56 to produce electric scanning fields, thereby to deflect the intensity modulated cathode ray vertically and horizontally so as to trace successive fields of parallel lines on the target of the tube to reconstruct the transmitted image.

For the purpose of more effectively receiving and reproducing a signal of the single sideband type transmitted, for example, from a transmitter such as described in connection with Fig. 1, the frequency changer 52 is arranged to develop such an intermediate-frequency signal that the intermediate-frequency carrier is normally located on one of the sloping sides of the band-pass characteristic of the selector 53, which is similar to that of the filter 19 of the system of Fig. 1 illustrated in Fig. 8.

Referring now more particularly to the synchronizing-signal-deriving apparatus 59, there is here provided an amplifier 60 having its input circuit connected to the output circuit of the intermediate-frequency amplifier 53 and its output circuit connected in turn to a broad single sideband selector 61. The selector 61 also preferably has a band-pass characteristic similar to that of the filter 19 of Fig. 1, that is, so designed that the intermediate-frequency carrier is located on one of its sloping sides. The amplifier 60 and selector 61 serve to provide a signal of sufficient amplitude to ensure proper operation of the succeeding parts of the apparatus 59. Due to the characteristics of the amplifier 53 and selector 61, the shift in the intermediate-frequency carrier from the sloping side of the band-pass characteristic to the uniform higher response portion thereof during the retrace periods effectively increases the amplitude of the carrier output of selector 61 so that the form of the wave developed in the output circuit of the selector 61 is as shown in Fig. 6.

Connected in cascade to the output circuit of the selector 61, in the order named, are a vacuum-tube limiter 62, a band-pass selector 63, a vacuum-tube amplifier 64, a modulation converter or selector 65, a double-diode rectifier circuit 66, and parallel-connected band-pass filters 67 and 68. The limiter 62 preferably comprises a pentode having a grid condenser 62a and leak resistor 62b, as shown, and has an operating characteristic as illustrated in Fig. 9, the points X-X' indicating generally the range of operation of the tube beyond both its upper and lower cutoff limits for any useful received signal. Due to the action of the limiter, only a small portion of the wave received from selector 61, such as that indicated at s in Fig. 6, is passed by the limiter 62. The condenser 62a and leak resistor 62b provide a self-biasing or stabilizing action for the limiter so that the interval s is always immediately below the peaks of the signal and independent of the signal amplitude. The half-envelope of the voltage developed in the output circuit of the limiter, therefore, is as illustrated by the curve of Fig. 7.

The selector 63 may comprise primary and

secondary windings 69 and 70, each broadly tuned by means of condensers 71 shunted by resistors 72 and so coupled and having such reactive constants as to pass broadly the band of intermediate signal frequencies comprised in the output pulses of limiter 62. The tube 64, together with selector 63, serves to couple the limiter 62 to the modulation converter or selector 65 and to prevent back coupling between the circuits. A suitable biasing battery 64a is preferably provided in the grid circuit of the tube 64, as shown. The selector 65 may be constructed similarly to the selector 63 and comprise transformer windings 73 and 74, each tuned by a condenser 75 shunted by a resistor 76. This selector, however, is preferably so tuned as to have a transmission characteristic such as is illustrated by the curve of Fig. 10, wherein relative gain in volts is plotted against frequency, in megacycles, relative to the intermediate-carrier frequency developed by the oscillator-modulator 52. Selector 65 is thus a band-pass selector for translating the carrier signal having a response characteristic with a sloping side and of a mean frequency so related to the normal predetermined frequency of the carrier that the latter is located on the sloping side. Thus, this selector comprises means responsive to periodic frequency variations of the received carrier wave and serves the purpose of converting the frequency shifts or modulation into amplitude variations; that is, the amplitude of its signal output varies in accordance with its input frequency shifts or variations.

The rectifier 66 may comprise a pair of diode rectifiers 77 and 78 connected across the secondary circuit of the selector 65 for full-wave rectification and provided with a load resistor 79. The voltage across load resistor 79 is applied negatively to the input circuits of the filters 67 and 68. The filters 67 and 68 are preferably tuned so that they are most responsive at frequencies corresponding to the cyclic carrier-frequency variations occurring during the line-retrace and field-retrace periods, respectively, that is, to frequencies of the oscillations generated by circuits 25 and 26, respectively, at the transmitter of Fig. 1. In the present case, for example, the filters 67 and 68 may be tuned to 1.0 and 0.24 megacycles, respectively. In order that these filters will have a reasonably rapid response, they are preferably designed with relatively wide band-pass characteristics, for example, of the order of $\pm 50\%$ of their respective mean resonant frequencies. The output circuits of the filters 67 and 68 may be connected to the line-scanning and field-scanning generators 57 and 58, respectively, for delivering synchronizing impulses thereto.

In the operation of the apparatus 59, the intermediate-frequency carrier and its single side-band of modulation frequencies are delivered from the amplifier 53 to the amplifier 60, wherein they are amplified and, in turn, delivered to the selector 61 and then to the limiter tube 62. Since the carrier signal is normally, that is, during trace or video-signal periods, located on the sloping side of the band-pass characteristic of selector 61, but during the retrace periods is shifted to the flat top of this characteristic, the frequency shifts, in effect, cause a substantial increase in the carrier amplitude output of selector 61 during each line-scanning and field-scanning period.

The tube 62 serves, as described above, to limit

the signal, thereby effectively to separate the synchronizing-signal components thereof from the video-signal components and to provide a signal in its output circuit, the half-envelope of which is illustrated in Fig. 7. This signal is delivered by way of the selector 63 and amplifier 64 to the modulation converter or selector 65 and therein effectively converted into a signal, the amplitude of which varies or is modulated in accordance with shifts or modulation of the frequency of the intermediate-frequency carrier. This signal is thereupon impressed upon the diode rectifier 66. The rectifier 66 functions to develop across its load resistor 79 a periodic impulse signal comprising two components each including recurring impulses. The frequency and duration of the impulses of one component correspond to the line-scanning impulses developed by the transmitter generator 12, while the frequency and duration of the impulses of the other component correspond to the field-scanning impulses developed by transmitter generator 13. Each of the impulses comprises successive cycles of oscillations, those of the line-scanning impulses being of the line-harmonic frequency and those of the field scanning impulses being of the field-harmonic frequency, as determined by the transmitter generators 25 and 26, respectively. The filters 67 and 68 are designed to be most responsive to such line-harmonic and field-harmonic frequencies, respectively, and thus comprise means responsive to the variations of the frequency of the carrier wave in a first predetermined manner for deriving line-synchronizing components and means responsive to variations of the frequency of the carrier wave in a different predetermined manner for deriving field-synchronizing components. It will be noted that the envelopes of the waves passed by the filters 67 and 68 constitute periodic waves comprising impulses occurring at the line-scanning and field-scanning frequencies, respectively, these impulses being impressed upon the generators 57 and 58, respectively, and serving to synchronize their operation in accordance with the corresponding generators 12 and 13 at the transmitter.

In the event that it is desired not to utilize the cyclic or harmonic variation feature of the invention, the generators 25 and 26 of the transmitter may be omitted so that the generators 12 and 13 and the apparatus 29 simply effect a single shift of the signal-carrier frequency into a portion of the frequency spectrum occupied by a sideband of the amplitude-modulated signal during each line-synchronizing and field-synchronizing impulse, which shift has a duration equal to that of its respective impulse. In this case, the receiver filters 67 and 68 may be omitted and any suitable signal duration responsive device may be substituted therefor. Such a device functions in a conventional manner to separate the line-synchronizing and field-synchronizing impulses in response to their relative durations and to deliver the derived line-synchronizing and field-synchronizing impulses to the generators 57 and 58, respectively. For this purpose, therefore, the input and output terminals of the filters 67 and 68 may be disconnected at the points indicated at A, B, and C, and a suitable duration responsive separator 80, such as indicated in Fig. 2a, may have its corresponding terminals, also indicated at A, B, and C, connected to these points. The device 80 may be of any suitable well-known design, such

as that shown in applicant's copending application, Serial No. 177,679, filed December 2, 1937, for Television scanning systems.

Moreover, if desired, the frequencies to which the carrier is shifted during the line-scanning and field-scanning pulses may be of different predetermined values, in which case the devices 65-68, inclusive, may be replaced by two selectors 81 and 82, as shown in Fig. 2b, sharply tuned to these respective frequencies and having individual rectifiers 83 and 84, suitably connected to the scanning generators 57 and 58, respectively. Similarly to Fig. 2a, the several points of connection for the circuits of Fig. 2b in the system of Fig. 2 are indicated at B, C, and D. With this or similar arrangements, if desired, a section of the modulation envelope below that represented at 5 may be selected by the limiter 62. For this purpose it is necessary only to adjust the value of the bias to an appropriate more negative value and to omit the self-biasing elements 62a and 62b.

It is to be noted that, in both arrangements described above, the advantage of an increase in synchronizing-signal amplitude, without any corresponding increase in power output at the transmitter is obtained by means of single sideband transmission and the special band-pass filter characteristic which has been described, employed at either or both the transmitter and receiver. It will, however, be appreciated that that single sideband feature may, if desired, be omitted from a system embodying the other features of the invention and, with conventional single- or double-sideband transmission and reception, the frequency-amplitude modulation feature alone may provide the required synchronizing signal. Moreover, the stages 19 and 20 may be omitted and the frequency shift network 29 be connected to the master oscillator 18 to shift its frequency during the retrace periods and, hence, that of the intermediate-frequency carrier developed by the modulator 17.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television broadcast system comprising a station for developing and transmitting a modulated-carrier wave including means for developing video-signal components during trace periods and synchronizing-signal components during retrace periods, and means for amplitude-modulating said carrier wave in accordance with said signal components of one of said types and for maintaining its frequency constant during all of said periods corresponding to said one of said types, and means for frequency-modulating said carrier wave in accordance with said signal components of the other of said types and for maintaining its amplitude constant during all of said periods corresponding to said other of said types, and a station for receiving and reproducing said transmitted wave including means responsive to amplitude modulation of the received carrier for detecting and utilizing said signal components of said one type, and means responsive to frequency modulation of the received carrier for

detecting and utilizing said signal components of said other type.

2. A television broadcast system comprising a station for developing and radiating a high-frequency modulated-carrier wave including means for developing video-signal components during trace periods and synchronizing-signal components during retrace periods, means for amplitude-modulating said carrier wave in accordance with said video-signal components, means for frequency-modulating said carrier wave in accordance with said synchronizing-signal components, means for directly radiating said amplitude- and frequency-modulated carrier wave, and a station for receiving and reproducing said transmitted wave including means responsive to amplitude modulation of the received carrier for detecting and utilizing said video-signal components, and means responsive to frequency modulation of the received carrier for detecting and utilizing said synchronizing-signal components.

3. A television broadcast system comprising a station for developing and transmitting a modulated-carrier wave representing successive trace and retrace periods including means for developing a carrier wave normally of a predetermined frequency, means for developing video-signal components and synchronizing-signal components, means for amplitude-modulating said carrier wave during trace periods in accordance with said video-signal components, means for shifting the frequency of said carrier wave during retrace periods into a portion of the frequency spectrum occupied by a sideband of said amplitude-modulated signal and in accordance with said synchronizing-signal components, and a station for receiving and reproducing said transmitted wave including means responsive to amplitude modulation of the received carrier for detecting and utilizing said video-signal components and means responsive to frequency variations of the received carrier for developing and utilizing said synchronizing-signal components.

4. A television transmitting system comprising means for developing a carrier wave, means for developing video-signal components during trace periods, means for developing synchronizing-signal components during retrace periods, means for amplitude-modulating said carrier wave in accordance with signal components of one of said types and for maintaining its frequency constant during all of said periods corresponding to said one of said types, means for frequency-modulating said carrier wave in accordance with signal components of the other of said types and for maintaining its amplitude constant during all of said periods of said other of said types, and means for transmitting said modulated-carrier wave.

5. A television transmitting system comprising means for developing a carrier wave, means for developing video-signal components, means for developing synchronizing-signal components, means for amplitude-modulating said carrier wave during trace periods in accordance with said video-signal components, means for frequency-modulating said carrier wave during retrace periods in accordance with said synchronizing-signal components, and means for directly radiating said modulated-carrier wave.

6. A television transmitting system comprising means for developing a carrier wave normally of a predetermined frequency, means for developing video-signal components, means for develop-

ing synchronizing-signal components, means for amplitude-modulating said carrier wave during trace periods in accordance with said video-signal components, means for shifting the frequency of said carrier wave during retrace periods into a portion of the frequency spectrum occupied by a sideband of said amplitude-modulation components and in accordance with said synchronizing-signal components, and means for transmitting said modulated and frequency-varied carrier wave.

7. A television transmitting system comprising means for developing a carrier wave normally of a predetermined frequency, means for developing video-signal components, means for developing line-frequency synchronizing impulses, means for developing field-frequency synchronizing impulses, means for amplitude-modulating said carrier wave during trace periods in accordance with said video-signal components, means for varying the frequency of said carrier wave for a first predetermined duration during at least a portion of said line-synchronizing impulses, means for varying the frequency of said carrier wave for a different predetermined duration during at least a portion of said field-synchronizing impulses, and means for directly radiating said modulated, frequency-varied carrier wave.

8. A television transmitting system comprising means for developing a carrier wave normally of a predetermined frequency, means for developing video-signal components, means for developing line-frequency synchronizing impulses, means for developing field-frequency synchronizing impulses, means for amplitude-modulating said carrier wave during trace periods in accordance with said video-signal components and for maintaining its frequency constant during all of said trace periods, means for varying the frequency of said carrier in a first predetermined manner during line-retrace periods, in accordance with said line-synchronizing impulses and for maintaining its amplitude constant during all of said line-retrace periods, means for varying the frequency of said carrier in a different predetermined manner during field-retrace periods in accordance with said field-synchronizing impulses and for maintaining its amplitude constant during all of said field-retrace periods, and means for transmitting said modulated, frequency-varied carrier wave.

9. A television transmitting system comprising means for developing a carrier wave normally of a predetermined frequency, means for developing video-signal components, means for developing line-frequency and field-frequency waves having trace and retrace periods, means for amplitude-modulating said carrier wave during trace periods in accordance with said video-signal components, means for varying the frequency of said carrier in a first predetermined manner and for a first predetermined duration during line-retrace periods, means for varying the frequency of said carrier in a different predetermined manner and for a different predetermined duration during field-retrace periods, and means for transmitting said modulated, frequency-varied carrier wave.

10. A television transmitting system comprising means for developing a carrier wave normally of a predetermined frequency, means for developing video-signal components, means for developing line-frequency and field-frequency scanning waves having trace and retrace periods, means for amplitude-modulating said carrier

wave during successive trace-scanning periods in accordance with said video-signal components, means for varying the frequency of said carrier in one or more successive cycles of predetermined frequency during successive line-retrace-scanning periods, means for varying the frequency of said carrier wave in one or more successive cycles of a different predetermined frequency during successive field-retrace-scanning periods, and means for transmitting said modulated, frequency-varied carrier wave.

11. A television transmitting system comprising means for developing a carrier wave normally of a predetermined frequency, means for developing video-signal components, means for developing line-frequency and field-frequency scanning waves having trace and retrace periods, means for amplitude-modulating said carrier wave in accordance with video-signal components during trace periods, means for shifting the frequency of said carrier wave with respect to said predetermined frequency and in accordance with synchronizing-signal components during retrace periods, a band-pass selector for translating said carrier and that one of its modulation sidebands on the side of said predetermined frequency to which said carrier frequency is shifted, said selector having a response characteristic with a sloping side and having a mean frequency so related to said predetermined carrier frequency that the latter is located on said sloping side, and means for transmitting the frequencies translated by said selector.

12. A television receiving system for receiving and reproducing a program transmitted by a carrier wave having amplitude modulation and frequency modulation, one of said types of modulation representing video-signal components during trace periods and the other of said types of modulation representing synchronizing-signal components during retrace periods and said carrier wave being of constant frequency during all of said periods corresponding to said amplitude modulation and of constant amplitude during all of said periods corresponding to said frequency modulation, comprising means for selectively receiving said carrier wave, means for detecting signal modulation of said one of said types to derive said video-signal components, means for detecting signal modulation of said other of said types to derive said synchronizing-signal components, and means for utilizing said derived components to reproduce the transmitted program.

13. A television receiving system for receiving and reproducing a program transmitted by a directly radiated carrier wave having amplitude modulation representing video-signal components during trace periods and frequency modulation representing synchronizing-signal components during retrace periods, comprising means for selectively receiving said signal, means for amplitude-detecting said carrier to derive said video-signal components, means for frequency-detecting said carrier to derive said synchronizing-signal components, and means for utilizing said derived components for reproducing the transmitted program.

14. A television receiving system for receiving and reproducing a program transmitted by a carrier wave normally of a predetermined frequency and amplitude-modulated in accordance with video-signal components during trace periods but having its frequency periodically shifted into a portion of the frequency spectrum oc-

cupied by a sideband of said amplitude-modulated signal and in accordance with synchronizing-signal components during retrace periods, comprising means for selectively receiving said carrier wave, means responsive to periodic frequency variations of said carrier wave for deriving said synchronizing-signal components, detecting amplitude-modulation means for deriving said video-signal components, and means for utilizing said derived components for reproducing the transmitted program.

15. A television receiving system for receiving and reproducing a program transmitted by a carrier wave normally of a predetermined frequency but having its frequency shifted for a first predetermined duration during line-retrace periods while its amplitude is maintained constant during all of the line-retrace periods and shifted for a different predetermined duration during field-retrace periods while its amplitude is maintained constant during all of the field-retrace periods and amplitude-modulated during trace periods in accordance with video-signal components while its frequency is maintained constant during all of said trace periods, comprising means for selectively receiving said carrier wave, amplitude-modulation detecting means for deriving said video-signal components, means responsive to frequency variations of said carrier wave of said first predetermined duration for deriving said line-synchronizing components, means responsive to frequency variations of said carrier wave of said different predetermined duration for deriving said field-synchronizing components, and means for utilizing said derived components for reproducing the transmitted program.

16. A television receiving system for receiving and reproducing a program transmitted by a carrier wave normally of a predetermined frequency and amplitude-modulated during trace periods in accordance with video-signal components but having its frequency shifted in a first predetermined manner during line-retrace periods in accordance with line-synchronizing components and having its frequency shifted in a second predetermined manner during field-retrace periods in accordance with said field-synchronizing components into a portion of the frequency spectrum occupied by a sideband of said amplitude-modulated signal, comprising means for selectively receiving said carrier wave, amplitude-modulation detecting means for deriving said video-signal components, means responsive to variations in the frequency of said carrier wave in said first predetermined manner for deriving said line-synchronizing components, means responsive to variations in the frequency of said carrier wave in said different predetermined manner for deriving said field-synchronizing components, and means for utilizing said derived components for reproducing the transmitted program.

17. A television receiving system for receiving and reproducing a program transmitted by a carrier wave normally of a predetermined frequency but having its frequency shifted in a first predetermined manner for a first predetermined duration during line-retrace periods in accordance with line-frequency synchronizing components while its amplitude is maintained constant during all of the line-retrace periods and having its frequency shifted in a different predetermined manner for a different predetermined duration during field-retrace periods in accordance with

field-frequency synchronizing components while its amplitude is maintained constant during all of the field-retrace periods, said carrier wave being amplitude-modulated during trace periods in accordance with video-signal components while its frequency is maintained constant during all of said trace periods, comprising means for selectively receiving said carrier wave, amplitude-modulation detecting means for deriving said video-signal components, means responsive to variations in the frequency of said carrier wave in said first predetermined manner and of said first predetermined duration for deriving said line-synchronizing components, means responsive to variations in the frequency of said carrier wave in said different predetermined manner and of said different predetermined duration for deriving said field-synchronizing components, and means for utilizing said derived components for reproducing the transmitted program.

18. A television receiving system for receiving and reproducing a program transmitted by a carrier wave and a sideband of amplitude-modulation frequencies representing video-signal components during successive trace periods, said carrier being normally of a predetermined frequency but shifted with respect to said predetermined frequency during successive retrace periods in accordance with synchronizing-signal components, comprising means for selectively receiving said carrier wave, amplitude-modulation detecting means for deriving said video-signal components, a band-pass selector for translating said carrier having a response characteristic with a sloping side and of a mean frequency so related to said predetermined frequency that the latter is located on said sloping side, means responsive to the signal output of said selector for deriving said synchronizing-signal components, and means for utilizing said derived components to reproduce the transmitted program.

19. A television receiving system for receiving and reproducing a program transmitted by a carrier normally of a predetermined frequency, but having its frequency varied through one or more cycles of one frequency during line-retrace periods and varied through one or more different cycles of a different frequency during field-retrace periods and amplitude-modulated during trace periods in accordance with video-signal components, comprising means for selectively receiving said carrier wave, amplitude-modulation detecting means for deriving said video-signal components from said received carrier wave, frequency-modulation detecting means for deriving from said received carrier wave said cyclic frequency modulation, resonant circuit means tuned to the respective frequencies of said one of said different cyclic variations for deriving synchronizing impulses, and means for utilizing said derived video-signal components and said synchronizing impulses for reproducing the transmitted program.

20. The method of transmitting and receiving a television program which comprises, developing video-signal components during trace periods and synchronizing-signal components during retrace periods, amplitude-modulating said carrier wave in accordance with said signal components of one of said types while maintaining its frequency constant during all of said periods corresponding to said one of said types, frequency-modulating said carrier wave in accordance with said signal components of the

other of said types while maintaining its amplitude constant during all of said periods corresponding to said other of said types, transmitting said modulated-carrier wave, selectively receiving said transmitted carrier wave, detecting said amplitude modulation of the received carrier to derive said signal components of said one type, detecting said frequency modulation of the received carrier to derive said signal components of said other type, and utilizing said derived components to reproduce the program.

21. The method of transmitting and receiving a television program, comprising developing video-signal components during trace periods and synchronizing-signal components during retrace periods, amplitude-modulating said carrier wave in accordance with said video-signal components, frequency-modulating said carrier wave in accordance with said synchronizing-signal components, directly radiating said modulated-carrier wave, selectively receiving said transmitted wave, detecting said amplitude modulation of the received carrier to derive said video-signal components, detecting said frequency modulation of the received carrier to derive said synchronizing-signal components, and utilizing said derived components to reproduce said program.

22. The method of transmitting and receiving a television program, comprising developing a carrier wave normally of a predetermined frequency and representing successive trace and retrace periods, developing video-signal components and synchronizing-signal components, amplitude-modulating said carrier wave during said trace periods in accordance with said video-signal components, shifting the frequency of said carrier wave during said retrace periods in accordance with said synchronizing-signal components into a portion of the frequency spectrum occupied by a sideband of said amplitude-modulated signal, transmitting said modulated, frequency-varied carrier wave, selectively receiving said transmitted wave, detecting said amplitude modulation of the received carrier to derive said video-signal components, detecting said frequency variations of the received carrier to derive said synchronizing-signal components, and utilizing said derived components to reproduce said program.

23. The method of transmitting a television program, comprising developing a carrier wave, developing video-signal components during trace periods, developing synchronizing-signal components during retrace periods, amplitude-modulating said carrier wave in accordance with signal components of one of said types while maintaining its frequency constant during all of said periods corresponding to said one of said types, frequency-modulating said carrier wave in accordance with signal components of the other of said types while maintaining its amplitude constant during all of said periods corresponding to said other of said types, and transmitting said modulated-carrier wave.

24. The method of transmitting a television program, comprising developing a carrier wave, developing video-signal components, developing synchronizing-signal components, amplitude-modulating said carrier wave in accordance with said video-signal components during trace-scanning periods, frequency-modulating said carrier wave during retrace-scanning periods in accordance with said synchronizing-signal components,

and directly radiating said modulated-carrier wave.

25. The method of transmitting a television program, comprising developing a carrier wave, developing video-signal components, developing line-frequency and field-frequency scanning waves having trace and retrace periods, amplitude-modulating said carrier wave in accordance with said video-signal components during trace-scanning periods, varying the frequency of said carrier in one or more successive cycles of one predetermined frequency during line-retrace scanning periods, varying the frequency of said carrier wave in one or more successive cycles of a different predetermined frequency during successive field-retrace scanning periods, and transmitting said amplitude-modulated and frequency-varied carrier wave.

26. The method of receiving and reproducing a television program transmitted by a carrier wave having amplitude modulation representing video-signal components during trace periods while its frequency is maintained constant during all of said trace periods and having frequency modulation representing synchronizing-signal components during retrace periods while its amplitude is maintained constant during all of said retrace periods, comprising selectively receiving said signal, detecting amplitude modulation of the received carrier to derive said video-frequency components, detecting frequency modulation of the received carrier to derive said synchronizing-signal components, and utilizing said derived components for reproducing the transmitted program.

27. The method of receiving and reproducing a television program transmitted by a carrier wave normally of a predetermined frequency and amplitude-modulated in accordance with video-signal components during trace periods but having its frequency shifted in accordance with synchronizing-signal components during retrace periods to a portion of the frequency spectrum occupied by a sideband of said amplitude-modulated video components, comprising selectively receiving said carrier wave, detecting said frequency variations of said carrier wave to derive said synchronizing components, detecting said amplitude modulation of said carrier to derive said video-signal components, and utilizing said derived components to reproduce the transmitted program.

28. The method of receiving and reproducing a television program transmitted by a carrier wave normally of a predetermined frequency but having its frequency varied in one or more successive cycles of one predetermined frequency during line-retrace-scanning periods and varied in one or more successive cycles of a different predetermined frequency during successive field-retrace scanning periods and amplitude-modulated by video-signal components during trace-scanning periods, comprising selectively receiving said carrier wave, detecting said amplitude modulation of the received carrier to derive said video-signal components, detecting the frequency modulation of the received carrier to derive said cyclic frequency modulation, selecting said cyclic variations of said one predetermined frequency to derive line-synchronizing impulses, selecting said cyclic frequency modulation of said different predetermined frequency to derive field-synchronizing impulses, and utilizing said derived video-signal components and synchronizing impulses to reproduce the transmitted program.

29. A television signal receiver adapted to receive a modulated-carrier wave amplitude-modulated by video-signal components during trace periods while its frequency is maintained constant during all of said trace periods and frequency-modulated by synchronizing-signal components to a predetermined frequency deviation during retrace periods while its amplitude is maintained constant during all of said retrace periods comprising, means selectively responsive to said predetermined carrier-frequency deviation for deriving synchronizing-signal components, means for amplitude-detecting said carrier wave to derive said video-signal components, and means for utilizing said derived video-signal components for reproducing the transmitted program.

30. A television signal receiver adapted to re-

ceive a directly radiated modulated-carrier wave amplitude-modulated by video-signal components during trace periods and frequency-modulated by synchronizing-signal components to a predetermined frequency deviation during retrace periods comprising, means frequency-selectively responsive to said predetermined carrier-frequency deviation for deriving synchronizing-signal components, amplitude-selective means coupled to said frequency-selective means for selecting only amplitude values above a predetermined value for synchronizing an operation of said receiver, means for amplitude-detecting said carrier wave to derive said video-signal components, and means for utilizing said derived video-signal components for reproducing the transmitted program.

ARTHUR V. LOUGHREN.

CERTIFICATE OF CORRECTION.

Patent No. 2,254,435.

September 2, 1941.

ARTHUR V. LOUGHREN.

It is hereby certified that error appears in the printed specification of the above numbered patent requiring correction as follows: Page 1, first column, line 47, for "increase" read --increases--; and second column, line 10, for "compounds" read --components--; page 4, first column, line 20, for "lator" read --lation--; page 5, first column, line 8, beginning with the words "The cycles" strike out all to and including "duration." in line 13; page 7, first column, line 32, for "that" read --this--; line 60, claim 1, strike out "and"; page 9, second column, line 65, claim 20, for "transmitteing" read --transmitting--; and that the said Letters Patent should be read with this correction therein that the same may conform to the record of the case in the Patent Office.

Signed and sealed this 3rd day of March, A. D. 1942.
